Fig. 5

Fig. 6

Fig. 7

Fig. 8

Fig. 9

Fig. 10

FIGURE 1 is a side elevational view of a power driven surface treating tool showing our new design as embodied in a portable powered surface scrubber, the opposite side being substantially similar;

FIGURE 2 is a bottom plan view thereof;

FIGURE 3 is a rear elevational view thereof;

FIGURE 4 is a front elevational view thereof;

FIGURE 5 is a top plan view thereof;

FIGURE 6 is a side elevational view, of a modified form of our design as embodied in a portable powered shoe polisher or the like, the opposite side being substantially similar;

FIGURE 7 is a bottom plan view of the modified form of the power driven surface treating tool shown in FIGURE 6;

FIGURES 8 and 9 are respectively rear and front elevational views of the modified form of power driven surface treating tool shown in FIGURES 6 and 7;

FIGURE 10 is a top plan view of the modified form

of power driven surface treating tool shown in FIGURES 6 through 9.

The dominant features of our design reside in the portions of the drawing shown in full lines.

We claim:

The ornamental design for a power driven surface treating tool, substantially as shown and described.
